UNITED STATES PATENT OFFICE.

ROY C. CASHNER, OF KANSAS CITY, MISSOURI, ASSIGNOR TO THE COASTER MANUFACTURING COMPANY, OF KANSAS CITY, MISSOURI, A CORPORATION OF MISSOURI.

COASTING-VEHICLE.

1,245,317.

Specification of Letters Patent.

Patented Nov. 6, 1917.

Application filed January 15, 1917. Serial No. 142,391.

To all whom it may concern:

Be it known that I, ROY C. CASHNER, a citizen of the United States, residing at Kansas City, in the county of Jackson and State of Missouri, have invented certain new and useful Improvements in Coasting-Vehicles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to coasting vehicles, and has for its principal object to simplify the control of the vehicle by combining steering and brake setting parts in a single operative element that is simple in construction and operation.

It is also an object of the invention to provide improved details of structure for facilitating the steering and brake setting operations.

In accomplishing these objects, I have provided improved details of structure, the preferred forms of which are illustrated in the accompanying drawings, wherein:—

Figure I is a perspective view of a coasting vehicle constructed according to my invention.

Fig. II is a longitudinal vertical section of the same.

Fig. III is a transverse section on the line III—III, Fig. II.

Fig. IV is a detail perspective view of the steering post and stop block.

Referring more in detail to the drawings:—

1 designates the body of the vehicle, and which preferably consists of a single board, comprising a rear seat portion 2 and forward, restrictive neck 3, the latter provided with a central, forwardly opening slot 4 through which the steering post is projected and within which the stop block is adapted for guided operation.

Mounted transversely beneath the seat 2 are spaced, V-shaped brackets 5—5' which preferably seat against battens 6 that are secured to the body by the bolts 7 whereby the brackets are attached to the seat, and rotatably mounted in bearing portions 8 at the points of the brackets is an axle 9, car-

rying the rear ground wheels 10. The 55 wheels 10 are preferably held in position at their inner sides by the brackets 5—5' and at their outer sides by cotter pins 11 that project through the outer ends of the axles.

Secured, preferably by bolts 12, to the under side of the neck 3 at opposite sides of the slot 4 are brackets 13—13', having transversely alining bearings 14—14' at their forward ends, and having downwardly projecting, V-shaped seat portions 15—15', and 65 secured to the downwardly and rearwardly projecting arms of said brackets 13—13' is a transverse bar 16, the ends of which project beyond the sides of the neck 3 to form foot rests 17—17' and have upstanding end 70 tips 18—18' for retaining the rider's feet on the rests.

Mounted in the bearings 14—14' is an axle 19 and pivotally mounted on the axle and extending rearwardly therefrom is a 75 block 20, having a shoulder 21 at its free end that is adapted to seat against the upper face of the cross bar 16 to limit the downward movement of the block.

Extending through an opening 22 in the 80 block 20, and revoluble therein is a steering rod 23, having a back-turned upper end portion 24 on which a steering handle 25 is fixed, preferably by a nut 26 that is threaded onto the end of the rod.

Fixed on the lower end of the rod 23 is a yoke 27 comprising spaced side members 28—28' having apertures 29—29' in their lower ends, within which an axle 30 is mounted to carry a front steering wheel 31. 90

Assuming that the parts are so constructed, a person sitting on the seat 2 places his feet on the foot rests 17—17' and guides the device by operating the handle 25 to turn the wheel 31 in the direction desired.

When it is desired to stop the vehicle, the handle 25 is pushed forwardly moving the block 20 on its pivotal mounting, so that the periphery of the guide wheel is brought into contact with the cross bar 16 and wipes the 100 bar to first retard travel of the vehicle and then completely stop the same.

Having thus described my invention what I claim as new therein and desire to secure by Letters-Patent, is:—

1. In a vehicle, the combination of a body, a brake bar, running gear comprising a steerable ground wheel movable to contact

with the brake bar, and a single handle for steering the ground wheel or moving the same to contact with the brake bar.

2. In a vehicle, a body, a block pivoted to the body on a transverse axis, a handle rod rotatable in the block, a ground wheel rotatably mounted on the handle rod, and a brake bar on the body positioned for engagement by the ground wheel when the block is moved on its transverse axis.

3. In a vehicle, a body member, a brake bar on the body member, a block pivoted to the body member on a transverse axis and arranged for engagement with the brake bar to limit its movement in one direction, a handle rod rotatably mounted in the block, and a ground wheel mounted on said rod and adapted for engagement with the brake bar.

4. In a vehicle comprising a body having a brake member thereon, a steering wheel movable to contact the brake member, and a handle for controlling said wheel to steer the same or effect contact of the wheel with the brake member.

5. In a vehicle, the combination with a body, a brake member on the body, a block pivotally mounted in said body, a handle rod rotatably mounted in said block, and a steering wheel on said rod movable by the rod to contact with said brake member.

6. A coasting vehicle comprising a body, a pair of supporting wheels mounted at one end of said body, a block pivotally mounted at the forward end of said body, a steering rod revolvably extending through said block, a steering wheel connected with said yoke, a handle on the upper end of said rod, and means for limiting the downward movement of the pivoted block.

7. A vehicle comprising a body, a pair of supporting wheels mounted at the rear of said frame, a block pivotally mounted at the forward end of said body frame and adapted to move vertically at its free end, brackets mounted at opposite sides of the frame, a cross bar attached to said brackets adapted to limit the downward movement of the said block, a steering rod extending through said block and revoluble therein, a yoke mounted on the lower end of said rod bearing against said block, a steering wheel mounted on said yoke, a handle on the upper end of said steering rod adapted to actuate the steering wheel and whereby said block may be moved on its pivotal mounting to bring said steering wheel into contact with the said cross bar.

8. In a vehicle, a body comprising a rear seat portion and a neck having a slot opening through its front end, a block pivotally mounted on a transverse axis and movable in said slot, a rod rotatably mounted in said block, and a steering wheel carried by said rod and adapted for contact with the brake bar when the rod is moved forwardly above its axis.

9. In a vehicle, a body comprising a rear seat portion and a neck having a slot opening through its front end, a transverse brake bar suspended from said body, a block pivotally mounted on a transverse axis and movable in said slot, a rod rotatably mounted in said block, and a steering wheel carried by said rod and adapted for contact with the brake bar when the rod is moved forwardly above its axis.

In testimony whereof I affix my signature.

ROY C. CASHNER.
